UNITED STATES PATENT OFFICE.

ARTHUR W. WALKER, OF MALDEN, AND BARTLETT M. SHAW, OF WATERTOWN, MASSACHUSETTS.

DESIGN FOR A RANGE.

SPECIFICATION forming part of Design No. 31,608, dated October 3, 1899.

Application filed September 11, 1899. Serial No. 730,173. Term of patent 14 years.

To all whom it may concern:

Be it known that we, ARTHUR W. WALKER, residing at Malden, and BARTLETT M. SHAW, residing at Watertown, county of Middlesex, and State of Massachusetts, citizens of the United States, have invented and produced a certain new and original Design for a Range, of which the following is a specification, reference being had to the accompanying drawings, forming a part thereof.

Figure 1 is a perspective view of a range, illustrating our design; and Fig. 2 is an enlarged top or plan view thereof.

The leading feature of our design consists in a range having a continuous oven-shelf and hearth, the front edge of the shelf and adjacent side edge of the hearth forming one continuous outwardly-convexed curve.

In the drawings the oven-shelf a is continued in the same plane into the hearth b ,

the front edge of the shelf and adjacent side edge of the hearth forming one continuous outwardly-convex curve a^x , while the front edge b^x of the hearth is similarly curved from side to side, the curves a^x and b^x being connected by a curve c of much shorter radius. 25

Having fully described our design, what we claim, and desire to secure by Letters Patent, is—

The design for a range, substantially as 30
herein shown and described.

In testimony whereof we have signed our names to this specification in the presence of two subscribing witnesses.

ARTHUR W. WALKER.
BARTLETT M. SHAW.
